UNITED STATES PATENT OFFICE

151,019

DESIGN FOR A WELL PUMP

Elmer E. Theis, Memphis, Tenn., assignor to Ace
Pump Corporation, Memphis, Tenn., a corpora-
tion of Tennessee

Application April 11, 1946, Serial No. 128,487

Term of patent 3½ years

(Cl. D65—1)

To all whom it may concern:

Be it known that I, Elmer E. Theis, a citizen of the United States, residing at Memphis, in the county of Shelby and State of Tennessee, have invented a new, original, and ornamental Design for a Well Pump, of which the following is a specification, reference being had to the accompanying drawing, forming a part thereof.

Figure 1 is a side elevation of a well pump, showing my new design with the flywheel drive pulley shown in Figure 3 omitted for convenience of illustration.

Figure 2 is an end elevation thereof.

Figure 3 is a perspective view of my new design.

The end of the pump, not shown, is substantially like the end shown. The side, not shown, is substantially like the side shown in Figure 3

without the bearing boss and flywheel drive pulley.

I claim:

The ornamental design for a well pump, substantially as shown and described.

ELMER E. THEIS.
